SEPARATING STRIP FOR THE SUBDIVISION OF CONCRETE OR THE LIKE STRUCTURES

Filed Jan. 24, 1927

Inventor:
Albert C. Fischer,

By atty.

UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

SEPARATING STRIP FOR THE SUBDIVISION OF CONCRETE OR THE LIKE STRUCTURES

Application filed January 24, 1927. Serial No. 163,053.

The present invention relates in general to laying concrete or the like structures or materials subject to expansion and contraction, and has for its primary object to provide means for controlling cracks as a result of expansion and contraction of such structures.

While the salient features of my present invention in some respects embrace the inherent qualities of an expansion joint installation, it is more particularly concerned with that type of installation more correctly referred to as a separating strip, or perhaps a contraction joint. Even more specifically, the installation is concerned with a cheap yet practical means of developing interlocking engagement between the concrete sections so as to prevent the sections from bulging along the line of separation, due to more or less severe expansion of the sections. This object is accomplished by developing a groove in one section with a complementary tongue in a confronting section fitting the tongue and thus locking the sections together.

This expedient has been suggested before and the novelty in the present invention resides in a cheap yet practical means of reducing the same to practice.

In the accompanying drawing I have illustrated the preferred embodiment of my invention, in which Figure 1 is a perspective view of the sheet material from which I produce the so-called separating strip.

Figure 2 is a perspective view of the trough shaped metal reinforcing form which is used in combination with the sheet material of Figure 1; and

Figure 3 is a perspective view showing the co-operative relationship of the parts of the built-up strip as it will appear when ready for use.

These tongue and groove separating strips have for the most part been usually constructed either from sheet metal or else a preformed plastic structure, either type being more or less expensive as compared to the present form.

In constructing the strip I propose to utilize a flexible sheet 5, such as illustrated in Figure 1. The same may be a sheet of saturated roofing felt or any other material suit-

able for the purpose, so long as it is cheaply acquired. For all practical purposes it should be waterproofed and capable of separating the sections of the concrete poured around the same.

To make the tongue and groove structure I prefer to employ a strip of sheet metal formed into a trough-like structure 6. Using this trough-like metal sheet as a form I present same longitudinally of the sheet or strip 5, and press the material of the strip into the form, using a suitable adhesive to retain the two parts together.

This assembly forms the required tongue and groove construction and develops a longitudinal reinforcing strip along the strip 5. The flat portions of the strip at the top and bottom of the tongue and groove thus formed, while somewhat reinforced and stiffened by the trough 6, are still too flexible to enable the separating strip to be installed by standing it up on edge and pouring the concrete around it, so that some suitable installing device must be used to obtain the best results. In this connection I will refer to an installing device shown in my co-pending application filed as of even date herewith, Serial No. 163,054.

This form of installing device will conveniently accommodate the present construction in that it will provide a backing board which will lie flush against the grooved side of the strip 5, and with the connected part overlying the opposite or tongue side of a strip 5 the stakes of the installing device will support the assembly so that the concrete may be poured against the same without disturbing the perpendicular alignment of the strip. After the concrete has been poured around the tongue side of the strip the backing board of the installing device is moved out of the way so that the concrete may be poured against the grooved side of the strip.

The pouring of the concrete on opposite sides of the strip will develop a groove in one section of the concrete and a tongue in the other, so that the sections are locked together. The flat portions of the strip 5 will separate the sections, so that for all practical purposes the sections are prevented from riding one up

over the other, and yet contraction of the concrete will enable the sections to move apart. In some instances the flat portion of the strip 5 above the tongue and groove would be imbedded below the surface of the concrete, and other times it may terminate flush with the surface of the concrete. If imbedded below the surface of the concrete it will be noted that the sections are not divided the entire depth of the concrete, but upon contraction in such cases any cracks that will occur will be controlled to such an extent that the cracks will follow out the weakened area, as a result of the imbedded strip, and they are thus prevented from occurring at irregular intervals and in irregular directions throughout the surface of the concrete. The flat portion below the tongue and groove structure will ordinarily terminate short of the base of the concrete, but in some instances the strips will extend to the subsoil.

In some instances I may desire to use transverse dowels or reinforcing rods in combination with this tongue and groove separating strip, in which event holes or openings 7 may be punched or otherwise formed in the metal troughs 6, and corresponding holes made in the sheet material formed into the trough so that the rods may be received transversely of the strip for imbedding therein concrete sections.

I would not expect the preferred embodiment of this strip to develop any special compensation for expansion of the concrete sections, at least so far as concerns compensating for expansion by inherent compressibility of the separating strip, but such a result could be very readily realized by producing the strip 5 of a thickness sufficient to permit for and compressibly yield to expansion of the sections. This additional thickness could be developed in various ways, one of which would be to use a multiple-ply sheet. Such a multiple-ply sheet may alternate with layers of adhesive mastic or the like, or else layers of adhesive mastic or the like may be applied to one or both sides of the flat portions of the strip 5.

I claim:

50. 1. A separating strip of the class described, comprising upper and lower flat portions of flexible sheet material and an intermediate tongue and groove portion connecting said upper and lower flat portions, and a metal reinforcement for said tongue and groove portions positioned intermediate the upper and lower edges of the flexible sheet.
55. 2. A separating strip of the class described, comprising upper and lower flat portions of flexible sheet material and an intermediate tongue and groove portion connecting said upper and lower flat portions, and a trough shaped metal reinforcement fitting over the tongue and groove portions, the edges of the reinforcement terminating along the line of

connection between the flat portions of the sheet and the intermediate tongue and groove portions.

Signed at Chicago, Illinois, this 13th day of January, 1927.

ALBERT C. FISCHER.
